[57] CLAIM

The ornamental design for a tire holder, as shown and described.

DESCRIPTION

FIG. 1 is a front perspective view of a tire holder, showing our new design;

FIG. 2 is a rear perspective view thereof, showing the hinged end in open position to allow removal of the good spare tire and placement of the damaged tire in the tire holder;

FIG. 3 is a front elevational view thereof;

FIG. 4 is a rear elevational view thereof;

FIG. 5 is a top plan view thereof;

FIG. 6 is a bottom plan view thereof;

FIG. 7 is an elevational view of one end thereof; and, FIG. 8 is an elevational view of the opposite end thereof.

The broken lines shown in FIG. 3 are for illustrative purposes only and form no part of the claimed design.
